ATTORNEY

UNITED STATES PATENT OFFICE.

WARD A. RUED, OF WOODWORTH, NORTH DAKOTA.

WATER-HEATER.

1,264,442.

Specification of Letters Patent. Patented Apr. 30, 1918.

Application filed June 1, 1917. Serial No. 172,266.

To all whom it may concern:

Be it known that I, WARD A. RUED, a citizen of the United States, residing at Woodworth, in the county of Stutsman and 5 State of North Dakota, have invented certain new and useful Improvements in Water-Heaters, of which the following is a specification.

This invention relates to water heaters, and 10 it more particularly relates to water heaters for domestic purposes.

One of the objects of this invention is to provide an improved means for utilizing the products of combustion of an internal combustion engine for heating water by maintaining a circulation of water through the hot products of combustion.

Another object of this invention is to provide a device of this character which is exceedingly simple of construction, and therefore comparatively inexpensive; and

Another object of the invention is to provide a device of this character which may be quickly and easily freed from soot deposited by the products of combustion.

Other objects and advantages may become apparent to those who read the following description and claims in connection with the appended drawings, in which,

30 Figure 1 is a view partly in side elevation and partly in vertical section, illustrating the manner in which my invention is applied.

Fig. 2 is a transverse vertical sectional view taken on the line 2—2 of Fig. 1; and

35 Fig. 3 is an enlarged fragmental horizontal sectional view, illustrating the manner in which the removable head of the exhaust chamber or muffler is secured in place.

Referring to these drawings in detail, in 40 which similar reference characters correspond to similar parts throughout the several views, the element 10 represents a hot water tank of any ordinary construction, the details of which do not constitute a part of

45 this invention. The tank 10 is provided with an opening adjacent to each end, and with pipe sections 11 and 12 which communicate with the respective openings and with a helical coil 13. This coil is inclosed within a

50 cylinder 14 which is provided with heads or end walls 15 and 16 and with an opening 17 adjacent to the head 16 and spaced therefrom. The head 15 is provided with an inlet opening which communicates with the 55 exhaust port of an engine, through the medium of pipe sections or connections 18 and

19; the engine being merely indicated by the reference character 20.

The head 15 is also provided with an aperture through which extends a pipe section 60 21 which constitutes the connection between the pipe section 12 and the coil 13, said pipe section 21 being axially parallel with the coil 13. The head 16 is provided with an outlet opening 22 which communicates with 65 an exhaust pipe 23 through the medium of a hollow extension 24, said hollow extension being located at one edge of said head 16.

The head 16 is provided with an annular flange 25 which fits snugly in the contiguous 70 end of the cylinder 14, while a shoulder 26 abuts against the end of the cylinder and prevents inward movement of the head 16 beyond a predetermined limit. The head 16 is also provided with an annular flange 26', 75 the latter serving to make the head exceedingly rigid and strong. A central opening 27 is provided in the head 16, and through this opening extends a hook-bolt 28, which carries a nut 29 which is seated snugly against 80 the outer surface of the head 16, while the hook 30 embraces the pipe section, within the cylinder 14, at a point adjacent to the extension of the coil which passes through the aperture 17. In order for the hook 30 to 85 thus embrace the pipe section, the latter is bent inward to a point approximate to the axis of the coil, and the said extension is disposed substantially along a radial line of said coil. Because of the pipe 13 being of 90 considerable rigidity and because of its engagement with the cylinder 14 where it passes through the aperture 17, the coil and its extension offer a considerable amount of resistance, while being somewhat yieldable 95 and springy. Therefore, when the head 16 is in place, as shown in Fig. 3, and the hook-bolt 27 is engaged therewith, as shown, the hook co-operates with the coil for holding the head 16 yieldingly in position, independ- 100

ently of any other means.

From the foregoing, it will be seen that the head 16 may be very quickly and easily removed, when desirable or necessary, for cleaning or repairing the interior and contents of the cylinder 14. It will also be seen that the hook 30 co-operates with the coil for preventing rotation of the hook-bolt when the nut 29 is being screwed on or off. It may be found desirable at times to flush the 110 cylinder 14, so as to wash out the soot, etc., and it is not considered beyond scope of this

invention to provide a hose connection and an outlet opening, with appropriate means for opening and closing the latter, so that the necessary or desirable flushing may be 5 accomplished.

In operation, the engine is started, and the exhaust passing from the engine, fills the cylinder 14 with the heated products of combustion, which pass out through the 10 opening 22 after the coil 13 and the water therein have absorbed a considerable amount of heat from the products of combustion, the latter continuing to flow through the cylinder 14 so long as the engine 20 is running. 15

There being relatively cold water in the tank 10, and the pressure of the water being greater at the bottom of the tank than at the top, the cold water also being heavier 20 than the hot water, the water begins to gravitate through the pipe 11 and to ascend through the pipe 12. In other words, a circulation is established through the tank 10, pipe sections 11 and 12 and coils 13. It will 25 be seen that the current of water through the coils 13 is moving in a direction opposite the direction in which the heated products of combustion pass through the cylinder 14, so that the heated products of combustion first come into contact with the coils which are hottest, so as to superheat the water in the coil immediately before it passes out through the pipe section 21 and up through the pipe section 12; while the relatively 30 cold water descending through pipe section 11 absorbs substantially all of the heat which remains in the products of combustion after said products have passed around and through the coils nearest the 35 head 15.

By the foregoing arrangement, I utilize a very large percentage of the heat contained in the products of combustion and apply the heat for the extremely useful purpose of 45 heating water for any of the various purposes in which hot water is desirable. However, in the present embodiment of my invention I have been using an improved device of this kind in connection with a domestic electric lighting system which is installed in connection with my dwelling, and the engine, corresponding to the elements 50 20, is provided with a self-starter which may be operated from any convenient point adjacent to or remote from the engine and 55 I find it very convenient to have a self-starter adjacent to one or more of the

sources of supply from the tank 10, so that when hot water is needed, I may start the engine and have only a short while to wait 60 until the water is heated for the purpose desired. From the foregoing it will be seen that I have provided a device which is extremely useful and which it is believed will become very popular and will meet with 65 great commercial success.

What I claim as my invention is:

1. A water heater, comprising a cylinder having a lateral opening in one end, heads closing the ends of the cylinder and having 70 inlet and outlet openings, respectively, the head contiguous to the end of the cylinder having the lateral opening being removable and having a central opening, a coil of pipe within the cylinder and having an end portion 75 extending diametrically inward, thence outwardly and passing through the lateral opening of the cylinder, and fastening means extending into the central opening of the removable head and engaging the diametrically inwardly extending portion of the coil to secure the removable head to the cylinder.

2. The combination of a cylinder, a coil of pipe therein, a cylinder head having an 85 opening therethrough, a hook-bolt seated in said opening and having its hook end in engagement with said coil, and a nut on said hook-bolt and co-operative therewith and with said coil of pipe for securing said head 90 yieldingly in position in said cylinder.

3. A heater comprising a cylinder having an inlet opening at one end and having a removable head at its other end, said removable head being provided with an outlet opening and with an opening which comprises a seat for a fastening element, a fastening element in said seat and provided with a hook, a coil of pipe in said cylinder and having one end extended through an 100 end wall of said cylinder and adapted to communicate with a water tank, the other end of said coil extending through the other end portion of said cylinder and adapted to communicate with said securing element for 105 removably securing said head in engagement with said cylinder.

In testimony whereof I affix my signature in presence of two witnesses.

WARD A. RUED.
